UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,118,290.

Specification of Letters Patent. Patented Nov. 24, 1914.

Application filed February 27, 1914. Serial No. 821,496.

To all whom it may concern:

Be it known that I, JOHN KIEWICZ, a citizen of the United States, residing at Boston, county of Suffolk, State of Massachusetts, have invented an Improvement in Sewing-Machines, of which the following description, in connection with accompanying drawing, is a specification, like characters on the drawing representing like parts.

10 This invention relates to sewing machines of that type which employ a bender mechanism for making a bend in the work at the time that the needle is given its work-penetrating thrust so that the needle may enter 15 and leave the work on the same side, thus forming a blind stitch. Sewing machines of this type are used for various purposes, among which might be mentioned the finishing of buttonholes in the manufacture of 20 button shoes. In the finishing of buttonholes by a sewing machine of this type the thrum ends of the buttonholes are gathered together and then are held in place by a blind stitch which is formed by the joint 25 operation of the bender and the stitch-forming mechanism.

The objects of my present invention are to provide a sewing machine of this type with an improved form of bender and its 30 operating mechanism which is simple in its construction, is so constructed that the operator has plenty of room above the work support to manipulate the work, is capable of quick adjustment to bring the bender 35 into different adjusted positions depending on the thickness of the material operated on, to provide a machine of this class which can be run at a high speed without producing any undesirable noise or vibration; to provide a construction which admits of the 40 needle bar being readily adjusted into its correct operating position, and to otherwise improve machines of this type, all as will be more fully hereinafter described and then 45 pointed out in the appended claims.

In order to illustrate the invention, I have shown it as it might be embodied in a buttonhole finishing machine, although I desire to state that it is equally applicable to 50 blind-stitch sewing machines adapted for other purposes.

Referring to the drawings wherein I have illustrated a selected embodiment of the invention, Figure 1 is a side view of a sewing 55 machine embodying my invention having a

part thereof broken out to better show some of the interior construction; Fig. 2 is a plan view with parts of the work support broken out; Fig. 3 is an underside view; Fig. 4 is a section on the line *a*—*a*, Fig. 1; Fig. 5 60 is a detail view of the bender and presser foot; Fig. 6 is a sectional view showing the way in which the needle bar carrier is adjusted; Fig. 7 is a section on the line *b*—*b*, Fig. 1.

65

The machine as a whole comprises a base frame presenting a work support, suitable stitch-forming mechanism situated beneath the work support, and a bender situated above the work support and adapted to form 70 bends in the material as the needle penetrates the latter, these being the parts which are commonly found in blind stitch sewing machines of this nature.

In the drawings the frame or base of the 75 sewing machine is shown at 1, and it may be constructed in any suitable way, the upper surface 2 thereof constituting a work support on which the work is sustained, and this work support is provided with a work-receiving groove 3 into which the work is bent by the bender 4, as will be presently described. Situated beneath the work support 2 is the usual stitch-forming mechanism comprising the needle 5 and the shuttle 6. 80 Both the needle and the shuttle are actuated from a driving shaft 7 situated beneath the work support 2. The shuttle 6 is herein shown as of the rotary type, it being sustained in a shuttle carrier 8 mounted on a stud 9 depending from the work support, which shuttle carrier is operated by bevel gears 10 from a shaft 11 that is driven from the main shaft 7 by any suitable mechanism which is not herein shown, 85 as it forms no part of the present invention.

The needle 5 is sustained by a needle bar 12 which reciprocates in a needle bar carrier 13 mounted on a shaft 14 about which it rocks to give the needle its vibratory movement. This rocking of the needle bar carrier 13 being secured from the usual switch cam 14 mounted on the shaft 7 and connections 15 leading from the switch cam to the carrier 13.

100

The needle bar is reciprocated by means of a link 30 connected to a crank disk 31 on the end of the driving shaft 7, as usual in machines of this type.

One of the features of my invention re- 110

lates to a construction by which the needle bar carrier can be adjusted vertically. In the operation of machines of this type it is essential that the path of the reciprocating needle should be at a definite distance from the top of the work support, and in the manufacture of machines it is sometimes difficult to assemble the parts so as to cause the needle to reciprocate in its proper path.

5 To obviate this difficulty, I have provided a construction whereby the needle bar carrier can be adjusted vertically after the machine is set up and assembled thereby to bring the needle into its correct position. With 10 this invention the manufacture of the machine is facilitated because if when a machine is built it is found that the needle is not operating in the correct position vertically, the needle bar carrier can be readily 15 adjusted to bring the needle into the correct position without the necessity of dismantling the machine and grinding off surfaces to get the desired fit. While any 20 suitable means for effecting this vertical adjustment of the needle bar carrier may be employed, I have herein shown one end 16 of the needle bar carrier as fitting and vertically adjustable on a block 17 which is secured to the under side of the work support 25 and also forms a bearing for the driving shaft 7. The end 16 of the needle bar carrier is held in its vertically-adjusted position on the block 17 by means of a screw 18 which operates in a slot in the block 17 and screw threads into the part 16. The end 30 of the shaft 14 is supported in a bearing 19 which is adjustably secured to the vertical wall of the base 1 by means of screws 20, said screws operating in slots in the bearing or support 19, and being screw-threaded into the wall of the base. By this means it 35 is possible to adjust the shaft 14 and the needle bar carrier vertically thereby to bring the needle into its correct position.

40 The bender 4 is a novel construction and is slidably mounted on a bender support 21 which is herein shown as having a general arcuate shape, and is rigidly secured to the top of the base frame by means of screws 50 22. This arcuate bender support which has a general inverted U-shape is provided with a curved or arcuate guideway 23 in which the shank 24 of the bender is received, said shank having a curved or arcuate shape corresponding to that of the guideway. The bender is held in the guideway by retaining screws 25 which screw into the bender support 21 and operate in slots 26 formed in the bender. The bender is operated by 55 means of an actuating lever 27 which is actuated directly from the driving shaft 7 and is herein shown as pivotally secured to the bender support at or near the top of the base frame 1. This actuating lever is shown 60 as having a hub 28 which is pivotally mounted on a stud 29 secured to the bender support 21, and the lever projects through the work support or top of the frame 1 and is acted on at its lower end by a cam 32 fast on the shaft 7, said cam preferably being of that type which will give positive movement to the actuating lever 27 in both directions. The upper end of the actuating lever 27 is connected to the bender by a link 33 which is shown as pivoted to the end of the shank of the bender at 34 and as adjustably secured to the upper end of the lever 27. With this construction it will be seen that the vibratory motion of the lever 27 will be communicated directly to the bender 4, and the shank of the latter will vibrate in the curved guideway 23. It will be understood, of course, that the cam 32 is so timed as to cause the bender to have its work-bending movement at the time that the needle is being given its penetrating movement so that at each forward thrust of the needle the bender will have bent the material into the groove 3 thereby to effect the formation of the blind stitch as usual in machines of this class. Provision is also made for effecting an adjustment of the bender relative to the actuating lever 27 so as to provide for bringing the tip of the bender into the proper position at each actuation thereof to cause the formation of the desired bend in the work. I also provide means whereby the bender will be permitted to give slightly relative to the actuating lever 27 so as to provide for operating on work which varies in thickness, which means is so constructed that the bender will operate noiselessly even when running at a high speed.

65 The link 33 is shown as passing loosely through an aperture in the upper end of the lever 27, and said end of the lever 27 is confined between an adjusting screw 40 screw-threaded to the link 33 and a spring 36 which rests against an adjustable collar 35 also screw-threaded to the link 33. I preferably provide a washer 38 between the spring 36 and the lever 27, and form said lever with a rounded surface 39 against which the washer rests so as to permit rocking movement of the lever 27 without any binding of the parts. The upper end of the lever 27 is also preferably formed with a rounded surface 42 and the nut 40 is concaved to fit this rounding surface 42, this construction being 70 adapted to permit of the necessary rocking movement between the lever 27 and the link without any binding of the parts. 41 is a lock nut which may be employed if desired.

75 The spring 36 will preferably be adjusted so as to have sufficient tension to resist the pressure of the bender when the latter is operating on thin material, so that under such circumstances, the spring will not give 75 during the bending operation. If, however,

a thick portion of the material comes under the bender, then the bender will have made the required bend in the material before the lever 27 has been given its complete movement, and under these circumstances the spring 36 will give sufficiently to prevent the bender from injuring the work. Moreover, the construction shown involving the spring 36 constitutes a bender-operating device which is noiseless in its operation. The position of the bender relative to the actuating lever 27 can be readily adjusted by operating the adjusting nut 40, the spring 36 being active at all times to take up any lost motion and hold the parts in relative position. The simple act of backing off the nut 40 will serve to lengthen the link 33, while screwing up the nut 40 will shorten the link thereby effecting the desired adjustment of the bender. In order to further provide means for reducing the noise incident to the operation of the machine and to provide means which will prevent the bender from coming into position to be engaged by the needle if the parts including the operating cam 32 become worn, I propose to provide a cushion stop for the bender which comes into action when the bender approaches the lower limit of its movement, which cushion stop will take up any lost motion due to wear of the parts. While this cushion stop may be made in various ways without departing from the invention I have herein illustrated a spring 60 which is adapted to be engaged by the lever 27 as the bender approaches the lower limit of its movement. This spring 60 is herein shown as secured to the base 1 of the machine and as situated immediately in the rear of the lever 27 just below the pivot thereof. When the bender is raised the spring will preferably have no contact with the lever, but when the lever is moved to depress the bender it will engage the spring and the spring acts during the latter part of the movement of the bender to take up any lost motion and to prevent an undue throw of the bender in case the cam 32 should become worn, and whenever the machine is run without any material to be acted upon.

It will be noted that the mechanism for operating the bender is comparatively simple, it comprising merely the actuating lever 27 and the link connection between the lever and the bender. Moreover, it will be noted that the lever 27 is pivoted to the bender support 21 near the base thereof and adjacent to the work support, and by this construction vibration of the parts is reduced. Moreover, I propose to so construct the actuating lever 27 that the weight thereof is approximately equally distributed above and below the pivotal stud 29, and, therefore, said lever is a balanced lever. This is important in a high speed machine because it

serves to reduce vibrations. I also desire to call attention to the fact that by forming the bender of arcuate shape operating in a similar-shaped guideway, I have provided a bender-operating mechanism having comparatively few parts and which are arranged so as to permit of high speed operation without any appreciable vibration.

Associated with the bender is the usual presser foot 43 which is normally held against the work by spring pressure, but which is lifted from the work whenever the machine is brought to rest. This presser foot 43 is sustained on a presser foot carrier 44 herein shown as a U-shaped member pivoted on a stud 45 secured to the bender support 21. This lever has a portion 46 which extends through the top 2 of the frame 1 and to which is secured a rearwardly-extending finger 47, to the end of which is attached a spring 48, the latter being connected to the frame at 49 and tending normally to keep the presser foot yieldingly held against the work. The driving shaft 7 is driven by any suitable means, and will also preferably be provided with a suitable stop motion for bringing the machine to rest with the parts in a predetermined position in the cycle of operations. This stop motion will also preferably coöperate with the arm 47 to raise the presser foot whenever the machine is thus brought to rest. Any suitable stop mechanism adapted to accomplish the above results may be employed, and I have herein shown one somewhat similar to that illustrated in my pending application Ser. No. 816,433, filed February 4, 1914. Since this stop motion is fully illustrated and described in said pending application, it is not necessary to refer to it in detail herein, but it will suffice to say that the treadle is connected by a link with an arm 65 on the rock shaft 66, and this rock shaft has an arm 67 thereon which is adapted to engage an arm or presser-foot-lifting member 52 that is mounted to turn on the spring-actuated slide 53 which controls the clutch mechanism. The arm 52 is, however, held from movement longitudinally of the slide 53. The driving shaft 7 has a stop cam 50 thereon which determines the particular point in the cycle of operations at which the machine will be brought to rest. So long as the treadle is depressed the member 52 is held out of engagement with the cam 50, but when the treadle is released said member 52 will be moved to bring the roll 51 thereon into engagement with the cam 50, said cam controlling the point at which the machine will be brought to rest. When the machine is brought to rest the raised portion of the cam 50 engages the roll 51 and depresses the arm 52, as seen in Fig. 4.

In my present invention the arm 47 con-

neeted to the lower end of the presser foot lever is extended so as to underlie the lifting part 52, and as a result when the machine is brought to rest and the lifting part 52 is depressed by the cam 50, said part acting on the extension 47 operates to raise the presser foot from the work against the action of the spring 49.

The bender support 21 is shown as provided at its free end with a bearing surface 70 against which a similar surface 72 on the presser foot engages, said bearing surface operating to steady the movement of the presser foot, as will be obvious.

15 In the foregoing specification and in the following claims I have used the term "work support" as indicating the top of the base frame 1 and not simply the portion thereof with which the work has contact.

20 While I have illustrated a selected embodiment of my invention, I do not wish to be limited to the constructional features shown.

Having described my invention, what I claim as new and desire to secure by Letters Patent is:—

1. In a sewing machine, the combination with a work support, of stitch-forming mechanism beneath the work support, an inverted U-shaped bender support, a vibrating bender mounted on said bender support, a bender actuating lever pivoted to said bender support extending through the work support and connected to the bender and by which the latter is operated.

2. In a sewing machine, the combination with a base frame, of an inverted U-shaped bender support secured at one end to the frame and provided with a longitudinally curved guide, a longitudinally curved bender operating in said guide, and means for actuating the bender.

3. In a sewing machine, the combination with a base frame, of an inverted U-shaped bender support secured at one end to the frame and provided with a longitudinally curved guide, a longitudinally curved bender operating in said guide, a bender-operating lever pivoted to said bender support and connected to the bender and means to actuate said lever.

4. In a sewing machine, the combination with a base frame, of a bender support secured thereto, an arcuate bender slidably sustained by said support for movement in an arcuate path, and means for operating the bender.

5. In a sewing machine, the combination with a base frame, of a bender support secured thereto, an arcuate bender sustained by said support, a bender-actuating lever pivoted to said bender support and connected to the bender, and means to vibrate said lever.

6. In a sewing machine, the combination

with a work support, of a driving shaft situated beneath the work support, a bender support situated above the work support and provided with an arcuate-shaped bender guide, an arcuate-shaped bender operating in said guide, an actuating lever pivoted to said bender support adjacent the work support and connected to the bender, and means for vibrating said bender-operating lever.

7. In a sewing machine, the combination with a work support, of a bender support provided with a curved bender-guiding groove, a curved bender operating in said groove, a bender-actuating lever, means to vibrate said lever, and a link pivotally connected to the bender and adjustably connected to said lever.

8. In a sewing machine, the combination with a work support, of a bender support situated above the work support, a bender slidably mounted on said bender support, a bender-operating lever, a link pivotally connected directly to the bender and adjustably and yieldingly connected to the lever.

9. In a sewing machine, the combination with a work support, of a bender support situated above the work support, a bender slidably mounted on said bender support, a bender-operating lever, a screw-threaded link pivotally connected to the bender and extending loosely through the lever, a collar on said link, a spring interposed between the collar and the lever, and an adjusting screw for adjusting the tension of the spring.

10. In a sewing machine, the combination with a work support, of an inverted U-shaped bender support situated above the work support, a bender slidably mounted on said bender support, means for actuating the bender, a presser foot and an inverted U-shaped presser foot carrier pivoted to said bender support.

11. In a sewing machine, the combination with a work support having a work-bending groove, of a bender support secured at one end to the work support and provided with a curved bender-receiving guide, a curved bender operating in said guide, a bender-actuating lever connected to the bender and pivotally connected to the bender support adjacent the work support, and means to vibrate said lever.

12. In a sewing machine, the combination with a base frame having a work supporting surface provided with a work-bending groove, of a bender support secured at one end to the frame and provided with a curved bender-receiving guide, a curved bender operating in said guide, a bender-actuating lever connected to the bender and pivotally connected to the bender support adjacent to but above the frame, and means to vibrate said lever.

13. In a sewing machine, the combination

- with a base frame having a work supporting portion provided with a work-bending groove, of a curved bender support secured at one end to the frame and provided with a 5 curved bender-receiving guide, a bender operating in said guide, a bender-actuating lever connected to the bender and pivotally connected to the bender support said lever extending through the latter adjacent the 10 frame, and means to vibrate said lever.
14. In a sewing machine, the combination with a base frame, of an inverted U-shaped bender support secured at one end to the base frame and provided with a guideway 15 curved in the direction of its length, a curved bender reciprocable in said curved guideway, a balanced lever pivoted to the bender support and connected to the bender, and means for operating said lever.
- 20 15. In a sewing machine, the combination with a work support, of stitch-forming mechanism including a horizontally-reciprocating needle bar situated beneath the work support, a vertically-adjustable needle 25 bar carrier in which said needle bar reciprocates, and means to reciprocate the needle bar.
16. In a sewing machine, the combination with a work support, of a horizontally-reciprocating needle bar situated beneath the work support, a needle bar carrier in which said needle bar reciprocates, and means at each end of the needle bar carrier for sustaining the same for vertical adjustment.
- 35 17. In a sewing machine, the combination with a work support, of a needle bar carrier situated beneath the work support, a shaft sustained by said carrier, a block to which one end of the carrier is secured for vertical 40 adjustment, a vertically-adjustable bearing for said shaft by which the other end of the needle bar carrier is sustained, a needle bar mounted in said carrier for horizontal reciprocating movement, and means to 45 actuate the needle bar.
18. In a sewing machine, the combination with a work support, of a bender support situated above the work support, a vibrating bender sustained by said bender support, an actuating lever for operating the bender, a driving shaft having a cam thereon for actuating the lever, and a cushion stop situated in the path of movement of the lever and positioned to be engaged by 55 said lever as it approaches the lower end of its movement, said stop being separated from the lever when the bender is raised.
- 60 19. In a sewing machine, the combination with a work support, of a bender support situated above the work support, a vibrating bender sustained by said bender support, an actuating lever extending through the work support for operating the bender, a driving shaft having a cam thereon for 65 actuating the lever, and a cushion stop situated to engage the lever and resist the work-bending movement of the bender as the latter approaches the lower limit of its movement.
20. In a sewing machine, the combination 70 with a work support, of a bender support situated above the work support, a vibrating bender sustained by said bender support, an actuating lever for operating the bender, a driving shaft having a cam thereon for actuating the lever, and a resilient member situated to be engaged by the actuating lever as the bender approaches the lower limit of its movement.
21. In a sewing machine, the combination 75 with a work support, of a bender support, a bender slidably mounted thereon, a lever extending through the work support and connected to the bender, and means beneath the work support for operating the lever.
22. In a sewing machine, the combination 80 with a base frame, of a bender support sustained thereby, a bender slidable on the bender support, a lever pivoted to said bender support and extending through the 85 top of the frame, and means beneath the frame to operate the lever.
23. In a sewing machine, the combination 90 with a base frame, of a bender support situated above the frame, a bender slidably 95 mounted on the bender support, a bender-operating lever extending through the top of the frame, a link pivotally connecting the bender and said lever, and means to actuate the lever.
24. In a sewing machine, the combination 100 with a base frame, of a bender support situated above the frame, a bender slidably mounted on the bender support, a bender-operating lever extending through the frame 105 top, a link pivoted directly to the bender and adjustably and yieldingly connected to the lever and means to operate the lever.
25. In a sewing machine, the combination 110 with a work support, of an inverted U-shaped bender support situated above the work support, a bender slidably mounted on the bender support, a lever pivoted to the bender support and connected to the bender, said lever extending through the 115 work support and means to actuate the lever.
26. In a sewing machine, the combination 120 with a work support, of a stationary bender support sustained thereby, a bender carried by the bender support for movement relative thereto, a lever extending through the work support and connected to the bender, and means beneath the work support to actuate the lever.
27. In a sewing machine, the combination 125 with a work support, of a stationary bender support sustained thereby, a bender car-

23
ried by the bender support for movement relative thereto, a lever pivotally mounted on the bender support and extending through the work support, and means beneath the work support to operate the lever.

28. In a sewing machine, the combination with a base frame, of an inverted U-shaped bender support supported by said base frame and provided with a longitudinally curved guide, a longitudinally curved bender operating in said guide, and means for actuating the bender.

29. In a sewing machine, the combination with a base frame, of a bender support sustained thereby and provided with a longitudinally curved guide, a longitudinally

curved bender operating in said guide, and means for actuating the bender.

30. In a sewing machine, the combination with a base frame, of a bender support, a 20 bender mounted thereon for movement relative thereto, a lever extending through the base frame and connected to the bender, and means beneath the base frame to actuate the lever.

25
In testimony whereof, I have signed my name to this specification, in the presence of two subscribing witnesses.

JOHN KIEWICZ.
